(57) **CLAIM**

I claim the ornamental design for a sheet pile connector, as shown and described.

DESCRIPTION

FIG. 1 is a perspective view of a sheet pile connector;

FIG. 2 is a front elevational view thereof;

FIG. 3 is a right side elevational view thereof; and,

FIG. 4 is a bottom plan view thereof.

The left side of the article is the same as the right, and so is not illustrated. The broken line showing of the connector is for the purpose of showing boundaries and forms no part of the claimed design.
